(57) CLAIM

The ornamental design for a bedstead, as shown and described.

DESCRIPTION

FIG. 1 is a perspective view of a bedstead showing my new design with a canopy in dashed lines;

FIG. 2 is a front elevational view thereof, with the finials in dashed lines; and,

FIG. 3 is a side elevational view, the opposite side being a mirror image thereof, with the finials in dashed lines.

The views of the bedstead not shown form no part of the claimed design. The broken lines depicting a canopy, finials, feet and the bed base represent environmental elements only and form no part of the claimed design.
